UNITED STATES PATENT OFFICE.

HARVEY E. MARVEL, OF WARSAW, INDIANA.

SAFETY ATTACHMENT FOR PUNCH-PRESSES.

1,238,548.

Specification of Letters Patent.

Patented Aug. 28, 1917.

Application filed March 15, 1917. Serial No. 155,128.

To all whom it may concern:

Be it known that I, HARVEY E. MARVEL, residing at Warsaw, in the county of Kosciusko and State of Indiana, have invented a new and Improved Safety Attachment for Punch-Presses, of which the following is a specification.

As is well known to those familiar with the operation of punch and die presses that in working the press, the operator, by carelessness or inattention to the running of the press, frequently trips the press while feeding the stock to or removing it from the press and in consequence a large per cent. of fingers and hands of punch or die press operators are thereby seriously injured.

The primary object of my invention is to provide simple, inexpensive and easily manipulated safety devices designed for being quickly adjusted and automatically released from the operative shaft before feeding the stock to or removing it from the press bed, so that accidental tripping of the press and consequent danger of injury to the hands of the operator are positively overcome.

My invention, in its generic nature, comprehends safety devices in the nature of improved clutch mechanism adapted for being co-operatively connected with the operating shaft of the press and the driver therefor, before putting the stock in position to be punched or embossed and for automatically disconnecting the said driver from a driving engagement with the operating shaft, and after the stock is placed in the desired position, and to instantly shift the parts whereby to put them back into position for being again actuated by the driver or power wheel.

Another object of my invention, is to provide certain improved features of construction, in the nature of clutch mechanism, in which detent devices are included, which, when initially set by the operator tend to keep the driver or fly wheel out of driving contact with the operating shaft until the parts are further adjusted by the operator for automatically effecting a readjustment of such parts for restoring the operating shaft into active condition.

With other objects in view that will hereinafter be explained, my invention consists in the improved features of construction and novel combination of parts that constitute my safety mechanism for punch or die presses and which will be first explained in

detail, specifically pointed out in the appended claims and illustrated in the accompanying drawings, in which:

Fig. 1 is a perspective view of so much of a punch press as is necessary to illustrate the general application of my "safety devices".

Fig. 2 is a perspective view of my invention as operatively applied, the fly or power wheel, with certain attached clutch members, being shown as removed from the punch actuating shaft, whereby to more clearly illustrate the co-operating parts.

Fig. 3 is a vertical section of my safety devices or clutch mechanism taken substantially on the line 3—3 on Fig. 6, the power or fly wheel being shown at the loosely running position and the shaft as held stationary.

Fig. 4 is a similar section, the wheel being shown as coupled with the shaft and the parts adjusted to cause the shaft to begin to turn with the wheel.

Fig. 5 is an inverted plan view, the parts being shown in the operative position when the shaft is turning in the direction of the arrow *a* and with the locking bar, hereinafter described, about to engage with a co-operating tripping clutch, to release the shaft from the fly wheel.

Fig. 6 is a horizontal section taken substantially on the line 6—6 on Fig. 2, looking in the direction of the arrow *b*, the tripping clutch being shown as having released the locking bar from the fly wheel.

Fig. 7 is a detail cross section on the line 7—7 on Fig. 3.

Fig. 8 is an inverted plan similar to Fig. 5, excepting that the safety dog and the released bar, hereinafter referred to, are about to be moved back to the normal or first position.

Fig. 9 is a view that illustrates, in perspective, the several parts that constitute my safety clutch mechanism, the parts being separated.

In the accompanying drawings, I have shown enough of the punch press to locate the operative parts that constitute my safety clutch mechanism and referring more particularly to Fig. 1, 1 indicated the base, 2 the machine bed, 3 the sides or standards and 4 the bearings at the upper front edges of the said side standards in which the operating shaft 5 is journaled, it being understood that the usual punch or stamping

mechanism, in practice, connects with the shaft and is actuated thereby in the usual manner when the said shaft is in motion.

Referring more particularly to Figs. 2 and 6, it will be noticed a hub 6 is fixedly mounted on the end of the shaft 5 next to the fly or power wheel 7 and the said hub carries a clutch member, that is hereinafter termed the locking bar 8, said bar being slidably mounted in a socket 80 formed in the said hub member and normally forced outwardly to its operative position, see Fig. 5, by a spring 81. Bar 8 also has a beveled notch 82 in its under edge, the reason for which will presently appear.

A clutch member 9 is pivotally mounted, at one end, on a stud 90 held on a bracket 10 secured on one of the side standards 3 adjacent the hub 6 on the operating shaft 5, and the front end of the said trip clutch member, which has a limited vertical swing, has a stop shoulder 91 at the inner end of a beveled tongue 92, the purpose of which will also presently appear.

39^a designates a pull rod that connects with an apertured ear 9^a pendent from the member 9 and which joins with a hand lever 39 located on the side standard, as is clearly shown in Fig. 1.

14 denotes a safety dog or lever, the inner end of which is pivotally mounted on a stud pin 15 located in a bracket 15^a on the frame standard 3 and the said safety lever, which swings in the horizontal plane, has its front end extended under the hub 6 on the shaft 5 and the said end formed with a segmental cam-like member 16 which, at times, coacts with a tripper pawl 17 mounted on the fly or driver wheel 7 and presently described in detail.

The safety dog lever 14 is secured, through a connection 18, with a release bar 19, one end of which passes through a suitable aperture 30, in the side standard 3, as is best shown in Fig. 3, by reference to which it will be seen that the outer end of the bar 19 extends under and locks the trip clutch member up to its normal or uppermost position and with its beveled tongue 92 located for being engaged by the notch

82 in the under side of the lock bar 8, as the shaft 5, with the wheel locked therewith, revolves in the direction of the arrow *c* on Fig. 7 and by reason thereof causes the lock bar 8 to pull inwardly within its socket 80, to the position shown in dotted lines on Fig. 6 and thereby moves into a locked engagement with the stop shoulder 91 to hold the shaft 5 from rotation, as the wheel 7, by reason of having been released from the lock bar 8 now turns loosely on the said shaft 5, it being understood that such relation of the parts continue until the said operative parts are readjusted by the operator.

By referring particularly to Figs. 2, 3

and 4, it will be seen, that the inner face of the fly or drive wheel has a series, preferably 3, of circumferentially arranged clutch sockets 22 into any one of which the clutch bar 8 projects during the operation of 70 clutching the shaft 5 to turn with the wheel 7, and with each of the said sockets 22 alines a transverse aperture 23 in each of which is mounted a pusher pin 24.

One of the pivoted arms or pawls 17, 75 mounted on the wheel 7, as hereinbefore referred to, is provided for coacting with each pusher pin and the said pawls 17 are so mounted that when swung in the direction, indicated by the arrow *x* on Fig. 4 (which 80 shows the wheel connected to the shaft by reason of the locking bar 8 extending into the socket 22), the said pawl 17 swings to the position shown in Fig. 3 which forces the pin in the direction of the arrow *y* and 85 thereby pushes the clutch or lock bar 8 back into its socket 80 and against the tension of its spring 81 and also out of a clutched relation with the wheel 7, the latter being thus released to run freely on the shaft 5. 90

As before noted, the safety dog or lever 14 has a cam segment 16, and since the said pawl 14 is connected with the release bar 19, when the said bar 19 is returned to the normal position, as presently explained, the 95 safety lever 14 is pulled over with such bar to the position shown in Fig. 8, the said dog 14 being limited in its movement, to the position shown, by a stop pin 26.

60 designates a lug roller on the shaft hub 100 6 for shifting the safety dog or lever 14 in a manner presently explained.

From the foregoing description taken in connection with the accompanying drawings, the complete construction, the general 105 operation and the advantages of my invention will be apparent.

In operating my safety devices, the operator, after he has placed the stock in the die, presses down the hand lever 28, at the left 110 side of the machine, which, through its connection 28^a with the release bar 19 pulls the said bar from under the trip member 9 which, under tension of a spring 29, remains at the elevated position shown in Fig. 115 3, while the release bar 19 assumes the position shown in Fig. 4.

In pulling the release bar over, as stated, the safety dog or lever is pulled over to the position shown in Fig. 8 and out of 120 the way of the pawls 17, as they move around with the wheel 7.

After shifting the parts controlled by the lever 28, the operator, with his right hand, depresses a lever 39 that joins, by flexible 125 connections 39^a with the trip clutch 9 and pulls the said lever down to the position shown in Fig. 4 and out of the path of the stop bar 8 and thereby trips the press and allows the shaft 5 and the wheel 7 to re- 130

volve together and effect a working action of the press.

After the shaft and the wheel are started, pressure on the lever 28 is released and in making a revolution, the stud roller 60 on the shaft hub 6 engages the safety lever 14, swings it over to the position shown in Fig. 6, and thereby brings the cam segment 16 in the path of the pivoted pawl 17 on the 10 now turning wheel, and as the said pawls 17 engage the cam 16, they are rocked to the position shown in Fig. 3 which pushes the pin inwardly and forces the clutch bar 8 from engagement with the wheel and thereby allows the wheel 7 to now run freely, as the rotation of the shaft 5 is again retarded by the lock bar 8 again contacting with the shouldered end of the pawl 14 which latter, by reason of the release of lever 39 is forced 20 back to its uppermost position in the path of the clutch or lock lever 8, see Fig. 3.

By reason of the safety lever 14 being attached to the release bar 19 in the manner stated, it follows that as the lever 14 is 25 swung over to the position shown in Fig. 6, the release bar is likewise pulled in the same direction and as it thus moves, its beveled edge 14^a engages the trip clutch member 9 and forces it up and holds it to the position 30 shown in Fig. 3, the advantage of the latter operation being apparent for the reason that if an operator is careless and holds the lever 39 and the trip clutch member 9 down too long, the action of the press puts the 35 trip member back to its proper place, which makes the press safe for a careless operator.

While the specific coöperative arrangement of the parts shown and described present a practical application of my invention, 40 it is understood I do not limit myself to the details shown, since they may be readily varied or modified without departing from my invention as set out in the appended claims.

45 What I claim is:

1. Safety means for punch presses and the like, comprising in combination with the operating shaft and a power wheel loosely mounted thereon; mechanism normally tending to lock the shaft to turn with the power wheel, a detent for holding the said mechanism out of locked engagement with the wheel, manually actuated means for tripping the said detent whereby to permit the 50 said mechanism to clutch the shaft to the wheel and further means actuated by the rotation of the wheel for shifting the said locking mechanism out of operative engagement with the wheel.

60 2. A rotary shaft, a power wheel loosely mounted thereon, clutch mechanism coöperating with the shaft and the wheel and normally out of interlocked engagement with the power wheel, the said mechanism including a locking element and means tending to

normally move the said element into a locked engagement with the power wheel, a manually released detent that holds the locking element to its wheel released position and adapted when tripped to effect the interlocking of the wheel and the shaft, whereby to rotate the shaft, and other means operated by the rotation of the shaft and the wheel for shifting the clutch mechanism to thereby release the shaft and the wheel from interlocked engagement. 70 75

3. In a mechanism of the character stated, a rotary shaft, a power wheel loosely mounted thereon, clutch mechanism that holds the wheel locked with the shaft, whereby to cause the wheel to rotate with the shaft to a predetermined degree and means operated by the rotation of the said wheel for shifting the clutch devices from engagement with the wheel, whereby to allow the wheel to 80 run loose on the shaft, and manually adjusted means adapted for being actuated by the freely rotatable wheel for restoring the clutch devices to the wheel and shaft interlocking adjustments. 85

4. In a safety control for punch presses and the like, the combination with the operating shaft and the power wheel loosely mounted thereon; of an automatic operating clutch mechanism for holding the wheel fixed on the shaft, means operated by the rotating wheel for shifting the clutch mechanism to release the wheel from locked engagement with the shaft, clutch tripping devices, manually operated means for setting the tripping devices and other means on the wheel for engaging the said tripping devices, whereby to shift the setting devices to restore the clutched relation of the wheel and the shaft. 90 95

5. In a mechanism of the character stated, a rotary shaft, a power wheel, means for holding the said shaft and wheel interlocked for a predetermined period and that automatically releases the wheel from an interlocked connection with the shaft at the end of such predetermined period and hand controlled means for restoring the said connections in condition for again effecting the interlocked relation of the shaft and the 100 105 wheel. 110

6. In a mechanism of the character stated, a rotary shaft, a power wheel, means for holding the said shaft and wheel interlocked for a predetermined period and that automatically releases the wheel from an interlocked connection with the shaft at the end of such predetermined period and hand controlled means for restoring the said connections in position for again effecting the 115 120 125 interlocked relation of the shaft and the wheel, said interlocking means including a clutch member on the shaft normally held for interlocking with the wheel, a shifter bar that engages the said member and means 130

on the wheel that engages the said bar and shifts it for moving the clutch member out of interlocked engagement with the wheel, to thereby cause the wheel to rotate loosely on the shaft.

7. In a mechanism of the character stated, a rotary shaft, a power wheel, means for holding the said shaft and wheel interlocked for a predetermined period and that automatically releases the wheel from an interlocked connection with the shaft at the end of such predetermined period and hand controlled means for restoring the said connections in position for again effecting the interlocked relation of the shaft and the wheel, said interlocking means including a clutch member on the shaft normally held for interlocking with the wheel, a shifter bar that engages the said member and means on the wheel that engages the said bar and shifts it for moving the clutch member out of interlocked engagement with the wheel, to thereby cause the wheel to rotate loosely on the shaft, a stop bar, a stop on the wheel for engaging the stop bar and manually operated means for setting the stop bar in position for being engaged by the wheel stop and other manually actuated means for shifting the stop bar out of the path of movement of the stop on the wheel and further means on the wheel for moving the said stop out of operative position when the manually controlled means is released.

8. The combination with a shaft, a continuously rotating power wheel loosely mounted on the shaft, clutch mechanism coöperative with the shaft and the wheel, manually operated means for adjusting the

said mechanism whereby to provide for placing the said mechanism into operative connection with the shaft and wheel, and means whereby to cause the shaft to rotate with the wheel, also coöperative with the shaft and wheel, for effecting a release of the wheel from the shaft after the wheel has rotated to a predetermined extent.

9. In a mechanism of the character stated, a rotary shaft, a power wheel loosely mounted on the shaft, a locking bar on the shaft, means tending to normally project said bar toward the wheel, a trip device that normally engages the lock bar and holds it back against the means that tend to push said bar outward, the said wheel having clutch seats for receiving the lock bar when the trip lever is disengaged therefrom, a safety dog having a cam portion, and a release bar that joins with the safety dog and which coacts with the trip bar to restore said bar to a normal or locked bar engaging position, means on the shaft that engage the safety dog for restoring the said release bar to the position stated and for setting the said dog to bring its cam portion to an operative position, pins slidably mounted on the wheel and adapted for engaging the clutched ends of the lock bars to move the said bars out of a clutch connection with the wheel, a pusher pivotally mounted on the wheel that engages the slidably pins and which have members that engage the cams on the safety dog as the wheel revolves, to thereby actuate the pivoted pushers for shifting the lock bar releasing pins.

HARVEY E. MARVEL.
